ATTORNEY.

UNITED STATES PATENT OFFICE

PHILIP DEAN, OF MADISON, WISCONSIN

KNOCK DOWN SHELVING

Application filed October 6, 1927. Serial No. 224,431.

This invention relates to knock-down shelving and has for an object the provision of an improved structure which may be easily erected by other than a skilled mechanic from units of simple and economical design.

Other more specific objects and advantages will appear from the following description of two illustrative embodiments of the present invention.

In the drawings:

Figure 1 is a view in perspective of an open type shelving structure embodying the present invention.

Fig. 2 is a transverse sectional view thereof taken substantially along the line 2—2 of Figure 3.

Fig. 3 is a fragmentary horizontal view, on a large scale, taken substantially along the line 3—3 of Figure 2.

Fig. 4 is a sectional view on the line 4—4 of Figure 3.

Fig. 5 is a view similar to Figure 3 illustrating a closed type of shelving structure.

Fig. 6 is a perspective view of the rear intermediate upright of the structure shown in Figure 5.

Fig. 7 is a similar view of the forward end upright of the structure shown in Figure 3.

The shelving selected for illustration comprises two sections A and B although any number of sections may be assembled from the structural units hereinafter described. The open type of shelving shown in Figures 1 to 4 and 7 includes two pairs of end uprights 10—11 and an intermediate pair of uprights 12—13, each being formed of sheet metal bent into channel form. The pair of intermediate uprights are rigidly connected

at their lower ends through appropriate sheet metal shoes or bridge-pieces 14 (Fig. 2) riveted or otherwise permanently secured thereto; and the several front uprights 11, 13, and 15 and connected by successive sections 15 of

an appropriate base board, applied against the rear faces thereof and removably secured thereto by pairs of appropriate downturned hooks 16, fixed to the base board sections adjacent the ends thereof and interlocked within openings 17 formed in the inner webs

of the uprights. In this instance each pair of hooks is formed by bending the ends of a strap 18, which is permanently fixed to a base board section and preferably countersunk in the face thereof. (See particularly Figs. 2 and 7.) Each base board section is slotted as at 19 to accommodate the bridge-pieces 14 hereinabove mentioned. Each end of the shelving is preferably closed by a suitable end panel 20 removably attached to the pairs of end uprights 10—11, by means of a vertical series of hooked brackets 21 permanently fixed to the inner face of each panel and interlocked within openings 22 formed in the inner webs of the uprights. The end panels 20 coating with the uprights assist the bridge-pieces 14 in affording the required fore and aft rigidity to the structure, the required lengthwise rigidity being effected by suitable diagonal brace rods 23 anchored at opposite ends in the side flanges of the uprights.

Each section of the shelving shown is equipped with individual shelf boards 25 which rest by gravity in appropriate metal stirrups or hangers 26, which extend transversely beneath the reduced ends 27 of the shelf boards, as indicated particularly in Figures 2 and 3. Each stirrup shown, comprises a horizontal shelf supporting web 28, which merges at opposite ends in upwardly inclined portions 29, which in turn terminate in downturned hook portions 30 adapted to interlock within openings 31 formed in the uprights. Each stirrup also includes a vertical flange 32 formed integral with the horizontal web and inclined portions to stiffen the stirrup and to retain the supported shelf against end play by abutting the end thereof. The inclined portions 29 provide the necessary clearance for easy assembly. The method of applying the stirrups is illustrated in Figure 4. The tapered form provided by the inclined portions 29 permits one end of the stirrup to be projected through the opening 31 in one upright, a distance sufficient to permit alignment of the other end of the stirrup with the corresponding opening 31 in the other upright, as indicated in dotted lines in Figure 4, so that the other end may then enter the other opening and the stirrup lowered

to the full line position shown, into interlocking relation within the openings of both uprights. The stirrup is then ready to receive the reduced end 27 of a shelf board, which is preferably bevelled off, as indicated at 33 (Fig. 2) to fit the inclined portions 29.

The top of the shelving is closed by a removable cover board 34 supported by stirrups 35 similar to the stirrups 26 hereinabove described. Each stirrup is provided with down turned end hooks 36 adapted to seat upon and interlock with notches 37 formed in the upper ends of the uprights. A cornice 38 fixed to the front and ends of the cover board provides a neat decorative finish for the top of the shelving, the side flanges of the front uprights being cut away to accommodate the cornice. The fronts of the several front uprights are preferably closed by appropriate wooden jams 39 fixed therein to improve the appearance of the shelving. As indicated in Figure 2 the base 40 of the cornice is preferably reduced so as to interlock with the jams 39.

The shelving shown in Figures 5 and 6 is similar in many respects to that hereinabove described. It includes pairs of similar end uprights 10'-11' with end panels 20' removably applied thereto in substantially the same manner, and a similar pair of intermediate uprights 12'-13', all of the uprights having similar openings 31' for receiving the hooked ends 30' of similarly formed shelf supporting stirrups 26'. In this instance, however, the back of the shelving is closed by appropriate panels 41, having hooked brackets 42 fixed to the edges thereof and projecting into interlocking relation with openings 43 formed in the side flanges of the uprights. These panels not only close the back of the shelving but coact with the uprights to afford sufficient rigidity to permit the elimination of the brace rods employed in the shelving first above described. In the shelving shown in Figures 5 and 6 the contents thereof are divided by an intermediate partition 44. This partition is made up of sections respectively disposed intermediate successive shelves, each section being provided with a pair of hooked brackets 45, similar to the brackets 42, projecting from the edges thereof. Brackets 45 project into and interlock with openings 46 (Fig. 6) formed in the inner webs of the uprights 12'-13' intermediate the openings 31'.

To assemble either form of shelving shown the end panels 20 or 20' are first attached to pairs of uprights 10-11 or 10'-11' to form the end units, and an intermediate pair of uprights 12-13 or 12'-13', rigidly connected by a bridge piece 14, are jointed to the end units by applying the base board sections 15 to the front uprights of the three pairs of uprights in the manner described. The rear uprights are then joined by applying the brace rods 23 or the rear panels 41. The top

board sections, with the cornice sections attached, are then applied, and the several shelf supporting stirrups inserted between the several pairs of uprights, after which the shelf boards are placed in position and the shelving is completed. If intermediate partitions are desired they are applied in the manner described above the successive shelves as they are inserted.

Various changes may be made in either of the embodiments of the invention hereinabove specifically described without departing from or sacrificing the advantages of the invention as defined in the appended claim.

I claim:

In a shelving structure the combination of a pair of uprights having opposed faces with openings formed therein, a shelf-supporting stirrup between said uprights said stirrup comprising a horizontal shelf-supporting web having upwardly inclined end portions, down turned hook portions on said end portions for interlocking engagement within said openings in said uprights, and an upright flange extending throughout the length of said web and connecting said end portions.

PHILIP DEAN.
